(57) **CLAIM**

The ornamental design for a slidable mount for an image device, as shown and described.

DESCRIPTION

FIG. 1 is an isometric view of a slidable mount for an image device;

FIG. 2 is a top view thereof;

FIG. 3 is a bottom view thereof;

FIG. 4 is a left side view thereof;

FIG. 5 is a right side view thereof;

FIG. 6 is a left end view thereof; and,

FIG. 7 is a right end view thereof.

The broken lines in FIGS. 1-3 illustrate portions of the slid-able mount for an image device which form no part of the claimed design.
